UNITED STATES PATENT OFFICE

168,254

SURVEYING INSTRUMENT

Leopold Churgin, New York, N. Y., and Donald N. Grundberg, Stoneham, Mass., assignors to C. L. Berger & Sons, Inc., Boston, Mass., a corporation of Massachusetts

Application January 24, 1952, Serial No. 13,206

Term of patent 14 years

(Cl. D52--1)

To all whom it may concern:

Be it known that we, Leopold Churgin and Donald N. Grundberg, citizens of the United States of America, residing in the Borough of Manhattan, city of New York, county of New York, and State of New York; and Stoneham, county of Middlesex, and State of Massachusetts, respectively, have invented a new, original, and ornamental Design for a Surveying Instrument, of which the following is a specification, reference being had to the accompanying drawing, forming part hereof.

Figure 1 is a view in perspective from one side of a surveying instrument showing our new design.

Figure 2 is an elevational view as seen from the other side of the instrument shown in Figure 1.

We claim:

The ornamental design for a surveying instrument, as shown.

LEOPOLD CHURGIN.
DONALD N. GRUNDBERG.
